PIPE BENDING MACHINE

Arthur L. Parker and Henry E. Hull, Cleveland,
Ohio; said Hull assignor to said Parker

Application January 16, 1940, Serial No. 314,042

20 Claims. (Cl. 153—40)

The invention relates generally to the art of tube or rod bending and primarily seeks to provide a novel machine structure in which tubes or rods of various sizes can be bent to the right or to the left with equal facility.

An object of the invention is to provide a novel machine of the character stated including novel multiple hand-actuated means for imparting movement to the bending mechanisms and which can be selectively used at the will of the operator accordingly as he wants to bend a rod or tube in one direction or the other and as the demand for a greater or lesser power application increases or diminishes because of variations in sizes of rods or tubes being worked upon at a given time.

Another object of the invention is to provide a machine of the character stated which embodies novel means for predetermining and visually indicating the angle of bend intended, and novel means for discontinuing the bending operation when the predetermined angle of bend has been attained.

Another object of the invention is to provide novel means for visually indicating the progress of attainment of the desired angle of bend regardless of the direction of bend.

Another object of the invention is to provide a machine of the character stated including a rotor, novel means for imparting movement to said rotor, novel means for selectively affixing individual radius blocks of different radii to said rotor for movement therewith, novel means for securing an end of a rod or tube to the selected radius block, and novel means for opposing the radius block and between which and said block the rod or tube is bent during movement of the block about the axis of the rotor.

Another object of the invention is to provide novel means for supporting tubes being bent from wrinkling or flattening.

Another object of the invention is to provide a novel reversible mounting for the rod or tube clamping and opposing means so that right or left bends can be made with equal facility.

Another object of the invention is to provide novel means for visually signalling approximate completion of the predetermined angle of bend.

Another object of the invention is to provide a machine of the character stated wherein is embodied bending mechanisms, manually actuated devices for imparting movement to said bending mechanisms, and means automatically effective upon completion of a predetermined angle of bend for locking said devices against additional movement.

Another object of the invention is to provide a machine of the character stated in which is included a radius block turning head, a multiple of selective gear couples of different ratios for imparting movement to the head, and a selective ratchet lever equipment for imparting increments of movement through said gear couples.

With the above and other objects in view that will hereinafter appear, the nature of the invention will be more fully understood by following the detailed description, the appended claims, and the several views illustrated in the accompanying drawings.

In the drawings—

Figure 1 is a plan view illustrating the invention.

Figure 2 is an enlarged plan view of the bending machine structure, parts being broken away and in section, and the pipe or rod clamping and radius block opposing devices being illustrated at one side of the radius block in full lines and in the reversed position at the opposite side of the radius block in dot and dash lines.

Figure 3 is a central vertical longitudinal sectional view, the section being taken substantially on the line 3—3 on Figure 2.

Figure 4 is a vertical cross section taken on the line 4—4 on Figure 2.

Figure 5 is a vertical cross section taken on the line 5—5 on Figure 2.

Figure 6 is a horizontal section taken on the line 6—6 on Figure 3.

Figure 7 is a detail vertical cross section taken on the line 7—7 on Figure 6.

Figure 8 is a fragmentary side view illustrating the stop bail and its mounting.

Figure 9 is a detail vertical cross section taken on the line 9—9 on Figure 6.

Figure 10 is a detail horizontal section illustrating one of the actuating handles.

Figure 11 is a vertical longitudinal section through the handle structure illustrated in Figure 10.

Figures 12 and 13, respectively, illustrate in plan and edge elevation a large size of radius block.

Figure 14 is a vertical cross section taken on the line 14—14 on Figure 1 and illustrating the mounting of the mandrel rod.

Figures 15 and 16 illustrate in plan and edge view a rotor disk equipped with driving lugs for engaging large sizes of radius blocks.

In the example of embodiment of the invention herein illustrated, there is included a housing shell 5 which is generally circular and closed

at the top and has a bottom opening defined by a flange 6 through the medium of which the machine can be secured upon a table or other suitable support. The housing shell includes an upwardly extended, concentric deck portion 7 which provides an abutment or stop walls 8 disposed at opposite sides of the center of the housing in the manner best illustrated in Figures 2 and 3 of the drawings, and a forwardly extended or enlarged portion 9.

The open bottom of the housing 5 is closed by a bottom plate 10 suitably positioned by dowel pin equipments 11 and which includes a center boss or bearing 12 vertically aligned with the bearing 13 formed on the housing shell 5. A spindle or driver shaft 14 is rotatably mounted in the bearings 12 and 13, and a large master gear 15 is secured upon the shaft 14 within the housing. The gear 15 has a heart cam groove 16 formed in its bottom face through the medium of which movement is imparted to the rollers 17 projecting vertically into the groove from the bend angle limiting plate 18 slidable in a rectilinear path in guides 19 projecting upwardly from the closure plate 10. The cam equipment 16 imparts rectilinear movement to the plate 18 and the plate is provided with a longitudinal center slot 20 which straddles the closure plate bearing 13 and permits this movement of the plate 18.

The upper end of the driver shaft or spindle 14 extends above the housing 5 and has a rotor disk 21 affixed thereto. The disk 21 carries a center boss 22 from which a center pin 23 projects in axial alignment with the spindle. A second or driving pin 24 is secured to the disk 21 and bears spaced parallel relation to the center pin 23 in the manner illustrated in Figures 2 and 3 of the drawings. Additional driving lugs 25 may be removably secured as at 26 to the upper face of the disk and extend radially and in equidistantly spaced relation about said disk. The purpose of the pins 23 and 24 and the lugs 25 will soon be described.

It will be observed by reference to Figure 3 of the drawings that the disk 21 is spaced above the main body portion of the housing shell 5, and a slide block mounting bar 27 is swingably mounted on the pintle 14 in this space so as to project radially from the pintle and be swingable about the axis thereof.

The bar 27 is centrally slotted so as to provide spaced, individual bar portions 28 and 29, and these bar portions are provided with equidistantly spaced cross apertures 30 for removably receiving a screw pin 31 which serves the purpose of anchoring the bearing block 32 having depending ears 33 straddling a selected one of the bar portions 28 or 29 in a selected position along said selected bar portion. The block 32 is equipped with a bore 34 for slidably receiving a plunger 35 which is slot and pin secured as at 36 against movement about its axis in said bore. The plunger is equipped with an axial threaded bore 37 for threadably receiving a captive screw 38 which is rotatable within the block bore through the medium of a hand wheel equipment 39. It will be obvious that as the hand wheel is rotated the plunger 35 will be projected from or retracted into the block bore according to the direction of rotation of said hand wheel.

At its projected end the plunger carries an elongated positioning block 40, said block being removably secured upon the plunger as at 41. The positioning block 40 has a slide plate 42 affixed to its lower surface and which is adapted

to be supported on and slide over the upper surface of the selected bar portion 28 or 29 upon which the block 32 happens to be mounted at the particular time. The upper face 43 of the positioning block 40 is smooth finished and has a pair of supporting pins 44 projecting therefrom in horizontal and parallel spaced relation. The pins 44 and the smooth face 43 serve to support and slidably position a slide block 45 which is rectangular in cross section and has each of its outer faces equipped with a distinct selective diameter tube confining groove 46. The pins 44 are removably attached to the block 40 and are used to support smaller sizes of slide blocks 45. When larger sizes of slide blocks 45 are used, in the bending of larger sizes of rods or tubes, the pins 44 are removed and the slide block in use is permitted to rest directly upon the end of the slide plate 42 which extends beyond the block 40. For this reason the extended end of the slide plate 42 is made as wide as the block 40, and thus a proper slide support is provided for the slide block 45, see Figure 2. It will be noted by reference to Figure 4 of the drawings that when smaller tubes are being bent the slide plate 42 extends over the edge portion of the rotor disk 21, but when larger sizes of tubes are being bent this slide plate is retracted with the block 40 and does not overlie the disk or interfere with the driving lugs which are then mounted thereon. By merely turning the slide block 45 to expose a selected groove thereof away from the smooth positioning face 43, the block can be utilized to properly engage tubes to be bent which are of various diameters.

A vise support bar 47 is pivotally mounted as at 48 on the driving pin 24 so as to be swingable about the axis of said pin. A slide 49 is mounted on said bar and includes depending retainers 50 which straddle and engage the sides of the bar. The slide also includes a shelf portion 51 for supporting a vise clamp block 52 which is identical in cross section with the slide block 45 but may be shorter in length. Like the slide block, the vise clamp block 52 is equipped with selective diameter tube opposing grooves 53 in the respective faces thereof. A slide adjuster screw 54 is held captive as at 55 in the slide 49 and is threaded through a bearing shoulder 56 projecting upwardly from the bar 47. The screw 54 is provided with a turning head equipment 57 and it will be obvious that by rotating this screw the slide 49 can be moved toward or from the driving pin 24.

A radius block generally designated 58 is provided and includes an aperture 59 for receiving the center pin 23 and another aperture 60 for receiving the driving pin 24. Radius blocks of various sizes are employed so as to adapt the machine for bending tubes or rods of various diameters, and each such block includes a concentric pending face 61 of a selected radius and an extended portion providing a clamping surface 62 merging as a tangent with the concentric peripheral or bending surface of the radius block. The surfaces 61 and 62 of each radius block are suitably grooved as at 63 to properly oppose the tube receiving groove equipments of the slide block 45 and the vise clamp block 52 hereinbefore referred to. It will be obvious by reference to Figure 2 of the drawings that a selected radius block can be positioned on the receiving pins 23 and 24 with the clamping surface 62 thereof presented at one side or the other of the disk. By thus reversibly mounting

the radius blocks they are adaptable for use in forming right or left hand bends in rods or tubes properly clamped thereto.

In Figures 12 and 13 of the drawings there is illustrated a large form of radius block 58 which is apertured as at 65 to receive the center pin 23 and as at 66 to receive the driving pin 24. The larger forms of radius blocks are also equipped with radially disposed recesses or sockets 67 at their upper and lower faces, and the lugs 25 projecting upwardly from the rotor disk 21 engage in driving relation in the sockets or recesses. It will be obvious that the larger forms also of the radius blocks are reversibly mounted on the rotor disk 21. These blocks also include a concentric bending surface 68 which merges into a tangentially extended clamping face 69, and these faces are grooved as at 70 for the purpose previously described.

A tube to be bent is indicated at 71, and in order to prevent wrinkling and flattening out of tubes of this nature during the bending process, there is provided a mandrel 72 which is selected from a range of such mandrels to freely fit in wall supporting relation within the tube to be bent. Each such mandrel is carried on a rod 73 removably secured as at 74 to an externally threaded anchor rod 75. The anchor rod 75 is extended through a cross slot 76 in a standard 77 projecting upwardly from the table or other support upon which the machine is mounted. A scale bar 78 is mounted on the standard over the slot 76 and is graduated progressively from a center point aligned with the axis of the rotor disk 21 toward each end of said scale bar. The anchor rod 75 is adjustably clamped to the standard 76 by clamp nuts 79, and by observance of the scale bar 78 the anchor rod 75 and the mandrel rod 73 can be readily positioned so as to bear tangential relation to the radius block mounted on the rotor disk 21 at the particular time.

It will be observed by reference to Figure 2 of the drawings that before commencement of a bending operation the vise supporting bar 47 and the slide block supporting bar 21 are swung to the same side of the rod disk 21 in the manner illustrated in full lines in this figure. When the bars are swung to the position illustrated, the bar portion 28 will be utilized as a support for the slide block. With the parts in this position the screw 54 is adjusted to force the vise clamp block 52 toward the radius block 58 so as to grip the end of the tube to be bent in the opposed groove surfaces 53 and 70. It should be understood that the mandrel 72 extends into and supports the inner walls of the tubes to be bent, the extended end of this mandrel terminating at a point directly opposite the axis of the center pin 23, which point represents the immediate point of bend during the performance of the bending operation. The hand wheel 85 is actuated to force the positioning block 40 toward the center pin 23, thereby to present the selected groove 46 of the slide block 45 in engagement with the opposed surface of the tube to be bent.

It will be obvious that by rotating the rotor disk 21 in a counter-clockwise direction, as viewed in Figure 2 of the drawings, the clamped end of the tube will be caused to move about the center pin 23 and the portions of the tube which are engaged by the rotating surface 61 of the radius block will be caused to conform to the shape of that surface. As the radius block is moved about the rotor disk, the vise supporting 75

bar 47 moves with said block. The slide block mounting bar 27 and the positioning block 40 mounted thereon are held stationary by engagement of the bar with the adjacent wall 8 of the housing, and the tube engaging groove 46 of the slide block 45 will cooperate with the mandrel 72 and the opposed radius block groove 63 in confining the tube against wrinkling or flattening. During the bending of the pipe, the pipe contacting slide block slides along over the supporting pins 44 and against the smooth positioning surface 43, and by this means abrasion of the tube is avoided.

It will be obvious that by reversing the positions of the bars 47 and 21 and the radius block 58 in the manner indicated in dot and dash lines of Figure 2, the machine can be adapted for bending pipes in the opposite direction. When the position of the bar 21 is reversed in this manner, it should be understood that the bearing block 32 is mounted on the arm portion 29 instead of upon the arm portion 28 as previously described.

Movement is imparted to the gear 15 and the rotor disk 21 in a manner latter to be described, and this movement, and of course, the bending operation performed by this movement, is stopped at a predetermined point by a stop block 80 which is slidable along the bottom plate 10 in the path of movement of the slidable bend angle limiting plate 18 hereinbefore referred to. The block 80 is secured to the end of a screw 81 threaded through an adjusting sleeve 82 which is rotatable in and has limited sliding movement in a bearing 83 and has its external surface provided with a worm screw portion 84. A hand wheel 85 and a stop collar 86 are mounted on the extended end of the sleeve 82, and the opposite end of the sleeve is externally threaded to adjustably receive an abutment member 87. A compression spring 88 is interposed between the member 87 and the opposed end of the sleeve bearing 89 carried by the housing.

If desired, the end of the bearing 89 opposed to the abutment member 87 can be utilized as a definite stop for limiting movement of the stop 80 with the slide member 18 following contact of these two elements to thereby terminate the bending operation after the intended bend angle has been attained. It will be obvious that in this use, the movement necessary to bring the abutment member 87 into contact with the stop end of the bearing, against the action of the spring 88, will serve to displace the sleeve 82 and hand wheel 85 longitudinally, and this movement of the hand wheel 85 can be observed by the operator as a visual indication of the attainment of the desired angle of bend.

By adjustment of the hand wheel 85 the position at which the stop 80 will intercept movement of the slide member 18 and bring about a termination of the bending operation can be altered at the will of the operator.

In order to visually indicate the intended angle of bend, the worm threaded portion 84 of the sleeve 82 meshes with a worm wheel 90 mounted on a stud shaft 91 supported as at 92 in the housing and carrying an indicator dial 93 which projects through a window 94 formed in the housing into position for having the intended angle of bend indicating indicia displayed on the dial accessible to the operator through said window. By observing the dial 93 the operator can readily observe the angle of bend predetermined by positioning of the stop 80.

As above described, the bearing and abutment equipments 89, 87 can be utilized as a positive stop for terminating the bending operation, but this termination of operation is preferably accomplished in a manner now to be described.

A stop bail 95 shaped to conform generally to the adjacent housing portion is pivoted as at 96 to the housing, and springs 97 mounted in suitable supporting lugs 98 projecting from the housing serve to constantly urge the bail upwardly. The bail is provided with a centrally disposed group of stop notches 99 disposed radially with relation to a central bearing boss 100 projecting upwardly from the base plate 10. A similar group of stop notches 101 is provided at each side of the bail in radial relation to each of the side bosses 102 projecting upwardly from the bottom plate, and these notches are adapted to engage and lock against movement actuator handle equipment soon to be described.

The upwardly pressed bail 95 includes a holding recess 103 which is engaged by a latching detent 104 projected through an aperture 105 in the housing and pivotally connected to one arm of a bell crank lever 106. The bell crank lever 106 is pivoted as at 107 on the housing and is spring pressed toward the latching position as at 108. The other leg of the bell crank lever is equipped with a trip finger 109 adapted to be actuated by the abutment element 87 each time the slide plate 18 engages the selectively positioned stop member 80 and effects a longitudinal displacement of the sleeve 82.

A center shaft 110 is vertically mounted in a bearing 111 formed in the housing and in the bottom plate center boss 100 hereinbefore referred to, and this shaft carries a pinion 112 which meshes with the master gear 15. The shaft 110 also carries a small pinion 113 at its upper end within a recess 114 formed in the housing extension 9. The recess is covered by a closure plate 115 having a sight window 116 through which calibrations on a dial 117 rotatably mounted in the recess can be observed by the operator. The dial is carried by a gear 118 which meshes with and receives rotation from the small pinion 113. The dial is calibrated as at 120 in opposite directions from a zero mark, and by observing the calibrations during the bending operation the operator can observe the progress of attainment of the desired angle of bend.

A larger spur gear 121 is secured upon the shaft 110 intermediate its upper and lower ends, and a shaft 122 is vertically mounted in bearings formed in the housing and in each of the side bosses 102 hereinbefore referred to. Like the shaft 110, each of the shafts 122 includes a driver pinion 123 which meshes with the spur gear 121. It will be obvious that by imparting rotation to any one of the shafts 110 or 122, rotation will be imparted to the master gear 15 and the rotor disk 21. When this rotation is imparted to the shaft 110, by engagement of a ratchet lever equipment later to be described with the gear 121 on said shaft, it is transmitted directly to the master gear 15 through the pinion gear 112 enmeshed therewith. When the rotation is imparted to one of the shafts 122, by engagement of a ratchet lever equipment with the pinion gear 123 thereon, it is transmitted indirectly from said gear 123 through the gear 121 with which said pinion gear meshes and the pinion gear 112 affixed to the shaft which carries the gear 121 to said master gear. See Fig-

ures 2, 3 and 8. An individual and identical ratchet lever equipment is employed for imparting rotation to each of said shafts.

Each ratchet lever equipment includes a sleeve 124 having apertured ears 125 for straddling or encircling the respective shaft 122 or 110 so as to mount the respective lever equipment for swinging movement about the axis of the respective shaft. A ratchet or driver plug 126 is slidably mounted within the sleeve and has a toothed end portion 127 engageable with the teeth of either of the pinions 123 or the larger gear 121.

Each lever includes a relatively flat handle portion 128 which merges into a cylindrical extension 129 rotatably mounted in the respective sleeve 124. Each cylindrical extension has a cross pin 130 projected therethrough, and the ends of each pin 130 project into an annular groove provided in a counterbore 131 in the sleeve 124, being confined in said groove by abutment rings 132 secured in the end of the sleeve by brazing or in any other suitable manner.

Each plug 126 includes a reduced extension 133 slidably mounted in the cylindrical extension of the handle and having limited longitudinal movement therein through the slot and pin connection 134. A compression spring 135 is interposed between each plug extension and the respective cross pin 130 and constantly tends to force the respective plug against the associated pinion or gear. A pull rod 136 is attached to each plug and extends through a portion of the handle 128 and is attached to a cross pin 137 extending through a longitudinal slot 138 in said handle. The cross pin 137 carries buttons 139 which may be actuated by the operator to retract the respective plug from contact with the associated gear or pinion. Each handle may also be turned about its axis to present the ratchet teeth of the plug in neutral position across the teeth of the respective gear or pinion, or for reversing the direction of projection of said ratchet teeth to adapt a given ratchet lever for imparting movement in a clockwise or counter-clockwise direction to the associated gear or pinion.

Oscillatory movement of the respective ratchet lever equipments is limited by the extent of the housing openings 140 through which these equipments project.

Each of the ratchet lever equipment sleeves 124 carries a depending lug 141 adapted to engage in one of the stop notches in the upper edge of the stop bail 95, and when this notch and lug engagement is effected, further actuation of the ratchet levers is rendered impossible.

When smaller forms of radius blocks are used, it may be found desirable to mount a spacer link 142 beneath said blocks in the manner illustrated in Figure 3 of the drawings.

By manipulation of either of the ratchet lever equipments disposed at a side of the machine, increments of movement can be imparted to the respective pinion 123, and through that pinion to the spur gear 121, pinion 112 and master gear 15 to the rotor disk 21 for effecting a tube or rod bending operation in the manner hereinbefore described. By a similar manipulation of the centrally disposed ratchet lever equipment, increments of movement can be imparted to the larger gear 121 and through its associated pinion 112 and the master gear 15 to the rotor disk 21. The ratchet lever equipment disposed at the center is operable at the will of the operator and operates through a gear couple having an 8-to-1 ratio

thereby serving to impart relatively quick movement to the bending parts. This ratchet lever equipment is used for rapidly bending small diameter rods or tubes. When it is desired to apply more power in the bending of larger tubes or rods, the ratchet lever equipments disposed at one side or the other of the central lever equipment are utilized either selectively or collectively and since the ratio of the gear couple through which increments of movements are imparted by this equipment is 30-to-1, the bending operation is performed at a slower rate and with correspondingly increased mechanical advantage. A skillful operator will find the selectively or collectively actuatable side mounted ratchet lever equipments very convenient and advantageous. Both of these lever equipment handles can be grasped simultaneously, and while one is being moved in the movement imparting direction the other can be moved in the non-effective or ratcheting direction, and vice versa, thereby facilitating the bending operation. Under certain conditions of use, one of the side mounted lever equipments and the centrally mounted lever equipment can be used cooperatively during a bending operation, despite the fact that each said lever equipment will be effective through a distinct gear ratio.

In performing a bending operation, an operator first positions the selected radius block in accordance with the size of tube or rod to be bent and the direction in which the bend is to be made. The slide block mounting and vise supporting bars 27 and 47 are suitably positioned and the blocks 45 and 52 are suitably brought into contact with the tube in the manner hereinbefore described. This being accomplished, the operator actuates the hand wheel 85 to suitably position the limiting stop 80 and at the same time position the dial 93 to indicate the intended angle of bend to be determined by said stop. The proper ratchet lever equipment is next actuated to impart increments of movements to the rotor disk 21 and the radius block mounted thereon. As the rotor disk 21 is moved, movement is imparted to the dial 117, and by observing the calibrations on this dial through the window 116 the operator always is aware of the progress of attainment of the desired angle of bend.

When the stop 80 is engaged by the slide plate 18 it yields slightly to movement of the slide plate and causes the abutment member 81 to engage the trip finger 109 and effect a releasing of the bail latching member 104. This releasing of the bail 95 permits the bail to be moved upwardly by the springs 97, and certain of the notches 101 and 99 will interlock with the latching lugs 141 depending from the ratchet lever equipments to positively lock said equipments against additional movement. By this means the bending operation is automatically terminated when the desired angle of bend has been attained.

It is, of course, to be understood that the details of structure and arrangement of parts may be variously changed and modified without departing from the spirit of our invention.

Having thus described the invention, what we claim as new and desire to secure by Letters Patent, is:

1. In a machine of the character described, a rotor, means for imparting clockwise or counter-clockwise movement to said rotor, a radius block supported on and movable with the rotor and having a peripheral face curved to conform to the curvature to which tubes are to be bent,

means for clamping a tube to be bent to the radius block for movement therewith, and means stationarily opposed to the radius block and engaged by a tube clamped against said block for causing the tube to bend about the block as it is turned, said clamping means and said block opposing means being shiftably mounted so that they can be moved from one side of the rotor to the opposite side thereof and thereby made to oppose either side of the radius block for effecting a bending of pipes to the right or to the left according to the positioning of said clamping and opposing means and the direction of the movement imparted to the rotor.

2. In a machine of the character described, a rotor, means for imparting movement to said rotor, a radius block movable with the rotor and having a peripheral face curved to conform to the curvature to which tubes are to be bent, means for clamping a tube to be bent to the radius block for movement therewith, means stationarily opposed to the radius block and engaged by a tube clamped against said block for causing the tube to bend about the block as it is turned, a master gear having driving connection with the rotor, a pinion gear meshing with the master gear, a large gear connected in driving relation with the pinion gear, a small gear meshing with the large gear, and two ratchet levers one having a pawl directly engageable with the large gear and one having a pawl directly engageable with the small gear, said levers being selectively operable for imparting increments of movement at selective speed rates to said rotor.

3. In a machine of the character described, a rotor, means for imparting movement to said rotor, a radius block movable with the rotor and having a peripheral face curved to conform to the curvature to which tubes are to be bent, means for clamping a tube to be bent to the radius block for movement therewith, means stationarily opposed to the radius block and engaged by a tube clamped against said block for causing the tube to bend about the block as it is turned, means for predetermined and visually indicating the angle of bend intended, means for visually indicating the progress of attainment of the angle of bend, and means for discontinuing the bending operation when the predetermined angle of bend has been attained.

4. In a machine of the character described, a rotor, means for imparting movement to said rotor, a radius block movable with the rotor and having a peripheral face curved to conform to the curvature to which tubes are to be bent, means for clamping a tube to be bent to the radius block for movement therewith, means stationarily opposed to the radius block and engaged by a tube clamped against said block for causing the tube to bend about the block as it is turned, said rotor movement imparting means including a manually operable lever, means for predetermined the angle of bend intended, and means engageable with said lever upon completion of the intended bend angle for locking the lever against additional movement.

5. In a machine of the character described, a rotor, manually operable means for imparting movement to said rotor, a radius block movable with the rotor and having a peripheral face curved to conform to the curvature to which tubes are to be bent, means for clamping a tube to be bent to the radius block for movement therewith, means stationarily opposed to the

radius block and engaged by a tube clamped against said block for causing the tube to bend about the block as it is turned, a member movable in a definite path with the rotor during the performance of a bending operation, a stop adjustably disposed in the path of travel of said member for intercepting movement of the member after attainment of a predetermined angle of bend in a tube being bent, stop adjusting means, means mounting the adjusting means for a limited amount of yielding movement with the stop following contact by said member, and means actuated by the yielding movement of said actuating means for locking the rotor against further movement.

6. In a machine of the character described, a rotor, means for imparting movement to said rotor, a radius block movable with the rotor and having a peripheral face curved to conform to the curvature to which tubes are to be bent, means for clamping a tube to be bent to the radius block for movement therewith, means stationarily opposed to the radius block and engaged by a tube clamped against said block for causing the tube to bend about the block as it is turned, a member movable in a definite path with the rotor during the performance of a bending operation, a stop adjustably disposed in the path of travel of said member and displaceable a limited distance thereby, said rotor movement imparting means including a manually operable lever, a lever locking member swingably mounted and constantly tending to engage the lever to secure it against movement, and locking member latching means automatically releasable by movement of displacement of said stop whereby the bending operations are terminated upon attainment of the intended angle of bend.

7. In a machine of the character described, a rotor, means for imparting movement to said rotor, a radius block movable with the rotor and having a peripheral face curved to conform to the curvature to which tubes are to be bent, means for clamping a tube to be bent to the radius block for movement therewith, means stationarily opposed to the radius block and engaged by a tube clamped against said block for causing the tube to bend about the block as it is turned, a member movable in a definite path with the rotor during the performance of a bending operation, a stop adjustably disposed in the path of travel of said member and displaceable a limited distance thereby, said rotor movement imparting means including two selective oscillatable manually operable ratchet levers adjustable about the axis of their length to be effective for movement imparting purposes in opposite directions, a third similarly oscillatable and adjustable ratchet lever and movement transmitting connections with the rotor for imparting movement in selective directions to said rotor at a speed of movement different from that imparted by the first-mentioned levers, a lever locking bail swingably mounted and constantly tending to engage the three levers collectively to secure them against movement, and locking member latching means automatically releasable by movement of displacement of said stop whereby the bending operations are terminated upon attainment of the intended angle of bend.

8. In a machine of the character described, a rotor, means for imparting movement to said rotor in clockwise or counter-clockwise directions, a radius block movable with the rotor and

having a peripheral face curved to conform to the curvature to which tubes are to be bent and grooved to partially embrace and confine said tubes against tendencies to wrinkle and flatten, 5 means for clamping a tube to be bent to the radius block for movement therewith, an opposing block grooved to partially embrace said tubes in tube confining cooperation with said radius block, means for slidably mounting the opposing block so that it can slide along a rectilinear path in contact with a tube being bent, said last-named means comprising a mounting bar, a positioning block having provision for definitely positioning and providing a longitudinal slide-way 10 support for said opposing block, means for slidably supporting the positioning block on said bar, and means for imparting movement of adjustment to the positioning block toward or from the radius block, said bar being swingable about the axis of the rotor for presenting the opposing block 15 at one side or the other of the rotor.

9. In a machine of the character described, a rotor, means for imparting movement to said rotor in clockwise or counter-clockwise directions, 20 a radius block movable with the rotor and having a peripheral face curved to conform to the curvature to which tubes are to be bent and grooved to partially embrace and confine said tubes against tendencies to wrinkle and flatten, 25 means for clamping a tube to be bent to the radius block for movement therewith, an opposing block grooved to partially embrace said tubes in tube confining cooperation with said radius block, means for slidably mounting the opposing block 30 so that it can slide along a rectilinear path in contact with a tube being bent, said last-named means comprising a mounting bar, a positioning block having provision for definitely positioning and providing a longitudinal slide-way support 35 for said opposing block, means for slidably supporting the positioning block on said bar, means for imparting movement of adjustment to the positioning block toward or from the radius block, said bar being swingable about the axis of the rotor for presenting the opposing block 40 at one side or the other of the rotor, a tube wall supporting mandrel having a moving fit within the tube being bent and stationarily held with its end terminating between the opposed surfaces of the 45 radius block and the opposing block, and means for longitudinally and laterally adjusting the position of said mandrel to adapt the same for cooperation with radius blocks of different sizes and at either side of said radius blocks.

50 55 10. A bending machine of the character defined in claim 9 in which the mandrel adjusting means comprises a transverse standard having a longitudinal mounting slot therein, a mandrel supporting rod adjustable longitudinally and transversely in said slot, an adjustment determining scale overlying said slot and graduated in opposite directions from a central mark aligned with the axis of the rotor, and means for securely clamping the rod in adjusted positions on said standard.

60 65 11. In a machine of the character described, a rotor, means for imparting movement to said rotor, a radius block movable with the rotor and having a peripheral face curved to conform to the curvature to which tubes are to be bent, means for clamping a tube to be bent to the radius block for movement therewith, means stationarily opposed to the radius block and engaged by a tube clamped against said block for causing the tube to bend about the block as it is turned,

a slide member, means including a heart cam movable with the rotor and effective to transmit to the slide member uniform increments of movement whereby the slide member is moved a uniform amount for each degree of bend of the tube being bent, and means disposed in the path of travel of the slide member for intercepting movement thereof after attainment of a predetermined angle of bend in a tube being bent.

12. In a machine of the character described, a rotor, means for imparting clockwise or counter-clockwise movement to said rotor, a radius block supported on and movable with the rotor and having a peripheral face curved to conform to the curvature to which tubes are to be bent, means for clamping a tube to be bent to the radius block for movement therewith, and means adapted to stationarily oppose the radius block and be engaged by a tube clamped against said block during rotation of the rotor and radius block for causing the tube to bend about the turning radius block, said clamping means and said radius block opposing means being shiftably mounted so that they can be moved from one side of the rotor to the opposite side thereof preparatory to a bending operation and thereby made to oppose the radius block at either side of the rotor for effecting a bending of pipes to the right or to the left according to the positioning of said clamping and opposing means and the direction of the movement imparted to the rotor, said radius block opposing means including an opposing block shiftable with said radius block opposing means and mounted for sliding movement in a rectilinear path for constant non-abrasive contact with the tube being bent and at the bending point regardless of the direction in which said bend is being made.

13. In a machine of the character described, a rotor, means for imparting clockwise or counter-clockwise movement to said rotor, a radius block movable with the rotor and having a peripheral face curved to conform to the curvature to which tubes are to be bent, means on said rotor for selectively mounting different sizes of radius blocks each having a grooved peripheral surface for bending a distinct size of tube, means for clamping a tube to be bent to the radius block for movement therewith, means adapted to stationarily oppose the radius block and be engaged by a tube clamped against said block during rotation of the rotor and radius block for causing the tube to bend about the turning radius block, said clamping means and said radius block opposing means being shiftably mounted so that they can be moved from one side of the rotor to the opposite side thereof preparatory to a bending operation and thereby made to oppose the radius block at either side of the rotor for effecting a bending of pipes to the right or to the left according to the positioning of said clamping and opposing means and the direction of the movement imparted to the rotor, said radius block opposing means including an opposing block shiftable with said radius block opposing means and mounted for sliding movement in a rectilinear path for constant non-abrasive contact with the tube being bent and at the bending point regardless of the direction of bend, and means for adjustably mounting said opposing block to properly oppose the selected sizes of radius blocks, said opposing block including a plurality of selectively presentable radius block opposing surfaces each

grooved to properly oppose the selected size of radius block groove.

14. In a machine of the character described, a rotor, means for imparting clockwise or counter-clockwise movement to said rotor, a radius block supported on and movable with the rotor and having a peripheral face curved to conform to the curvature to which tubes are to be bent, means for clamping a tube to be bent to the radius block for movement therewith, means adapted to stationarily oppose the radius block and be engaged by a tube clamped against said block during rotation of the rotor and radius block for causing the tube to bend about the turning radius block, said clamping means and said radius block opposing means being shiftably mounted so that they can be moved from one side of the rotor to the opposite side thereof preparatory to a bending operation and thereby made to oppose the radius block at either side of the rotor for effecting a bending of pipes to the right or to the left according to the positioning of said clamping and opposing means and the direction of the movement imparted to the rotor, said radius block including an extended portion having a clamping surface merging as a tangent with the curved peripheral surface of said block, and means for reversibly positioning the radius block on said rotor so as to enable presentation of the tangentially extended portion thereof at one side or the other of the rotor center in opposition to the shiftably mounted clamping means.

15. In a machine of the character described, a rotor, means for imparting clockwise or counter-clockwise movement to said rotor, a radius block supported on and movable with the rotor and having a peripheral face curved to conform to the curvature to which tubes are to be bent, means for clamping a tube to be bent to the radius block for movement therewith, means adapted to stationarily oppose the radius block and be engaged by a tube clamped against said block during rotation of the rotor and radius block for causing the tube to bend about the turning radius block, said clamping means and said radius block opposing means being shiftably mounted so that they can be moved from one side of the rotor to the opposite side thereof preparatory to a bending operation and thereby made to oppose the radius block at either side of the rotor for effecting a bending of pipes to the right or to the left according to the positioning of said clamping and opposing means and the direction of the movement imparted to the rotor, said radius block including an extended portion having a clamping surface merging as a tangent with the curved peripheral surface of said block, said rotor having a center pin and an off center driving pin extending therefrom in spaced parallel relation, and said radius block also including mounting sockets in its respective faces for freely receiving said pins so that the radius block can be reversibly mounted with the tangentially extended portion thereof disposed in opposition to the shaftably mounted clamping means at either side of said pins.

16. In a machine of the character described, a rotor, means for imparting clockwise or counter-clockwise movement to said rotor, a radius block supported on and movable with the rotor and having a peripheral face curved to conform to the curvature to which tubes are to be bent, means for clamping a tube to be bent to the radius block for movement therewith, means

adapted to stationarily oppose the radius block and be engaged by a tube clamped against said block during rotation of the rotor and radius block for causing the tube to bend about the turning radius block, said clamping means and said radius block opposing means being shiftably mounted so that they can be moved from one side of the rotor to the opposite side thereof preparatory to a bending operation and thereby made to oppose the radius block at either side 10 of the rotor for effecting a bending of pipes to the right or to the left according to the positioning of said clamping and opposing means and the direction of the movement imparted to the rotor, said radius block including an extended portion having a clamping surface merging as a tangent with the curved peripheral surface of said block, said rotor having a center pin and an off center driving pin extending therefrom in spaced parallel relation, said radius block also including mounting sockets in its respective faces for freely receiving said pins so that the radius block can be reversibly mounted with the tangentially extended portion thereof disposed in opposition to the shiftably mounted clamping means at either side of said pins, said shiftable clamping means being mounted on a bar swingable about the axis of the driving pin, and said shiftable radius block opposing means being mounted on a bar swingable about the axis of the center pin.

17. In a machine of the character described, a rotor, means for imparting clockwise or counter-clockwise movement to said rotor, a radius block supported on and movable with the rotor and having a peripheral face curved to conform to the curvature to which tubes are to be bent, means for clamping a tube to be bent to the radius block for movement therewith, and means adapted to stationarily oppose the radius block and be engaged by a tube clamped against said block during rotation of the rotor and radius block for causing the tube to bend about the turning radius block, said rotor movement imparting means including a toothed driving wheel connected in driving relation with the rotor and an oscillatable ratchet lever having a pawl engageable with the wheel, said lever being adjustable about the axis of its length to render it effective for imparting clockwise or counter-clockwise movement to said wheel.

18. In a machine of the character described, a rotor, means for imparting clockwise or counter-clockwise movement to said rotor, a radius block supported on and movable with the rotor and having a peripheral face curved to conform to the curvature to which tubes are to be bent, means for clamping a tube to be bent to the radius block for movement therewith, and means adapted to stationarily oppose the radius block and be engaged by a tube clamped against said block during rotation of the rotor and radius block for causing the tube to bend about the turning radius block, said rotor movement imparting means including a toothed driving wheel connected in driving relation with the rotor and an oscillatable ratchet lever having a pawl engageable with the wheel, said lever being adjustable about the axis of its length to render it effective for imparting clockwise or counter-clockwise movement to said wheel, and a second 70 similarly oscillatable and adjustable ratchet

lever and pawl equipment and a second toothed driving wheel engaged thereby and coupled in driving relation with the rotor for driving the same at a speed of movement different from that imparted by engagement of the first mentioned lever with the first mentioned wheel.

19. In a machine of the character described, a rotor, means for imparting clockwise or counter-clockwise movement to said rotor, a radius block supported on and movable with the rotor and having a peripheral face curved to conform to the curvature to which tubes are to be bent, means for clamping a tube to be bent to the radius block for movement therewith, means adapted to stationarily oppose the radius block and be engaged by a tube clamped against said block during rotation of the rotor and radius block for causing the tube to bend about the turning radius block, said clamping means and said radius block opposing means being shiftably mounted so that they can be moved from one side of the rotor to the opposite side thereof preparatory to a bending operation and thereby made to oppose the radius block at either side of the rotor for effecting a bending of pipes to the right or to the left according to the positioning of said clamping and opposing means and the direction of the movement imparted to the rotor, said radius block including an extended portion having a clamping surface merging as a tangent with the curved peripheral surface of said block, said rotor having a center pin and an off center driving pin extending therefrom in spaced parallel relation, and said radius block also including mounting sockets in its respective faces for freely receiving said pins so that the radius block can be reversibly mounted with the tangentially extended portion thereof disposed in opposition to the shiftably mounted clamping means at either side of said pins, said shiftable clamping means being mounted on a bar swingable about the axis of the driving pin, said shiftable radius block opposing means being mounted on a bar swingable about the axis of the center pin, and two 30 abutments one at each side of said center pin against one or the other of which abutments the radius block opposing means supporting bar is automatically held against movement with the tube being bent during a tube bending operation.

20. In a machine of the character described, a rotor, means for imparting clockwise or counter-clockwise movement to said rotor, a radius block supported on and movable with the rotor and having a peripheral face curved to conform to the curvature to which the tubes are bent, means for clamping a tube to be bent to the radius block for movement therewith and means movable with the tube and opposed to the radius block for engaging the tube at the immediate point of bend for maintaining the tube in contact with the radius block, said clamping means and said movable opposing means being shiftably mounted so that they may be moved from one side of the rotor to the opposite side thereof for effecting a bending of tubes to the right or left according to the position of the clamping and opposing means and the direction of movement imparted to the rotor.
